 FIG. 4 is a first side view thereof;
 FIG. 5 is a second side view thereof;
 FIG. 6 is a top view thereof;
 FIG. 7 is a bottom view thereof;
 FIG. 8 is a perspective view of a second embodiment of a label sheet assembly with matrix cuts;
 FIG. 9 is a front view thereof;
 FIG. 10 is a back view thereof;
 FIG. 11 is a first side view thereof;
 FIG. 12 is a second side view thereof;
 FIG. 13 is a top view thereof;
 FIG. 14 is a bottom view thereof; and
 FIG. 15 is a perspective view of a third embodiment of a label sheet assembly with matrix cuts;
 FIG. 16 is a front view thereof;
 FIG. 17 is a back view thereof;
 FIG. 18 is a first side view thereof;
 FIG. 19 is a second side view thereof;
 FIG. 20 is a top view thereof; and
 FIG. 21 is a bottom view thereof.
 FIG. 22 is a perspective view of a fourth embodiment of a label sheet assembly with matrix cuts;
 FIG. 23 is a front view thereof;
 FIG. 24 is a back view thereof;
 FIG. 25 is a first side view thereof;
 FIG. 26 is a second side view thereof;
 FIG. 27 is a top view thereof;
 FIG. 28 is a bottom view thereof; and
 FIG. 29 is a perspective view of a fifth embodiment of a label sheet assembly with matrix cuts;
 FIG. 30 is a front view thereof;
 FIG. 31 is a back view thereof;
 FIG. 32 is a first side view thereof;
 FIG. 33 is a second side view thereof;
 FIG. 34 is a top view thereof;
 FIG. 35 is a bottom view thereof; and
 FIG. 36 is a perspective view of a fifth embodiment of a label sheet assembly with matrix cuts;
 FIG. 37 is a front view thereof;
 FIG. 38 is a back view thereof;
 FIG. 39 is a first side view thereof;
 FIG. 40 is a second side view thereof;
 FIG. 41 is a top view thereof;
 FIG. 42 is a bottom view thereof;
 FIG. 43 is a perspective view of a sixth embodiment of a label sheet assembly with matrix cuts;
 FIG. 44 is a front view thereof;
 FIG. 45 is a back view thereof;
 FIG. 46 is a first side view thereof;
 FIG. 47 is a second side view thereof;
 FIG. 48 is a top view thereof;
 FIG. 49 is a bottom view thereof; and
 FIG. 50 is a perspective view of a seventh embodiment of a label sheet assembly with matrix cuts;
 FIG. 51 is a front view thereof;
 FIG. 52 is a back view thereof;
 FIG. 53 is a first side view thereof;
 FIG. 54 is a second side view thereof;
 FIG. 55 is a top view thereof; and,
